O. A. KREUTZBERG

CARBURETOR FOR POWDERED COAL

Filed Feb. 20, 1924

UNITED STATES PATENT OFFICE.

OTTO A. KREUTZBERG, OF LAKE BLUFF, ILLINOIS.

CARBURETOR FOR POWDERED COAL.

Application filed February 20, 1924. Serial No. 694,005.

The purpose of this invention is to provide improved means for mixing air and powdered fuel such as powdered coal for immediate use in a heating furnace or under 5 a power boiler and susceptible of regulation through fairly wide limits for varying the intensity of the fire and the heat given off thereby. It consists of certain features and elements in combination as herein shown and 10 described and as indicated by the claims.

In the drawings:—

Figure 1 is a front elevation partly in section as indicated at line 1—1 on Figure 2, illustrating a coal carbureting machine embodying this invention.

Figure 2 is a side elevation showing the coal feed hopper in section.

Figure 3 is a top plan view with the fuel feeding mechanism removed from the feed 20 chamber.

In preparing powdered fuel such as finely pulverized coal for combustion there is of course an ideal proportion preferably to be maintained between the quantity of fuel and 25 the quantity of air furnished for its combustion. Obviously any considerable excess of air over that required for complete combustion will tend merely to absorb heat units and carry them off through the stack while 30 insufficient air will produce a smoky flame and will either encrust the entire combustion chamber with soot or cause combustible carbon to be carried away in the smoke. In various plants the proportion of air supplied 35 with the fuel and that supplied through the draft doors may be varied according to local conditions but in any plant it is desirable to furnish a considerable proportion of the air already mixed with the pulverized fuel.

40 The apparatus of this invention is designed to do this and since the volumetric output of a blower varies quite uniformly with its speed through a considerable range, it is found that by mechanically connecting the fuel feeding 45 device to the blower so that a certain quantity of powdered fuel is released for each revolution of the blower rotor, a practically constant mixture of air and fuel can be maintained through a considerable range of 50 speeds.

As shown in the drawings, the blower is housed in a casing, 1, surmounted by a feed chamber, 2, which may be understood as being located directly below a storage hopper for powdered fuel indicated in dotted lines at 3. The blower shaft, 4, carrying the blast

wheel, 5, is connected directly to a drive motor, 6, whose speed may be varied in any desired manner; preferably the motor is of a variable speed type designed for efficient 60 operation throughout a considerable range of speeds. Within the feed chamber, 2, a feeder wheel, 7, is carried by a shaft 8, at whose outer end outside the chamber, 2, there is fixed a bevel gear, 9, meshing with a similar gear, 10, on a vertical shaft, 11. Said shaft, 11, carries a large worm gear, 12, which is driven at reduced speed by a worm, 13, on motor shaft, 4. Thus the speed of the feed wheel, 7, is definitely proportioned to the 70 speed of the blast wheel, 5.

The wheel, 7, spans an outlet or discharge port in the lower part of the chamber, 2, giving access directly to the blower casing, 1, at its upper portion while the discharge 75 mouth, 14, of the blower is shown at the lower portion of the casing and at the same side of the shaft, 4. As the blades, 15, of the wheel, 5, rotate from the outlet, 8, to the discharge mouth, 14, it results that the powdered 80 fuel admitted at the outlet, 8, is picked up by the fan blades, 15, and carried through almost a complete revolution of the wheel, 5, in the direction indicated by arrow X on Figure 2, before arriving at the discharge mouth, 14, 85 thus affording ample opportunity for intermixture of the powdered coal with the air handled by the blast wheel. Though the fuel falls by gravity from the chamber, 2, into the path of the blades, 15, it will be widely 90 dispersed through the air current by centrifugal force so that substantially all the fuel will be discharged from the fan wheel during the first revolution and will pass with the air to the combustion chamber of the furnace. 95

To agitate the powdered material in the hopper, 2, just sufficiently to prevent it from packing or clogging therein I provide a cage-like structure comprising two disks, 16, carried on an axle, 17, and connected in spaced 100 relation by tie rods, 18. The peripheral portion of each disk, 16, is notched and the material cut from the notches is folded up to form blades, 19, radially arranged. These blade portions of the disks, 16, laterally overlap the feeder wheel, 7, and a stud, 20, projecting from one face of said wheel engages any one of the notches between the blades, 19, so that with each rotation of the feed wheel, 7, the agitator is advanced a few degrees 110 about its axis so as to break up any packing of the fuel mass in the chamber, 2. As the

feed wheel, 7, rotates in the chamber, 2, its outwardly open pockets will fill with powdered fuel and as these pockets pass the discharge port, 8, they will empty their loads into the blower. However, the angular extent of each pocket is something less than the thickness of the bottom wall of the chamber, 2, which the pocket traverses in approaching the port, 8, or leaving it; thus there is always at least one side of one pocket interposed between the feed chamber, 2, and the edge of the port, 8, so that the feeder wheel constitutes a complete closure for the port and no powdered fuel is permitted to leak past the wheel 15 at any position thereof.

I claim:

1. In an apparatus for mixing powdered fuel and air, an air blast wheel and a casing therefor having a tangential discharge mouth, 20 a feed hopper for the fuel mounted adjacent the blast wheel casing and formed with an outlet positioned to direct the fuel toward the periphery of the blast wheel, and means

for positively controlling the feed of fuel from the hopper in fixed relation to the speed 25 of the blast wheel.

2. In an apparatus for mixing powdered fuel and air, a centrifugal blast wheel and a casing therefor, a feed hopper for the fuel having an outlet leading into the casing adjacent the periphery of the blast wheel and circumferentially remote from the air outlet 30 of its casing, said hopper outlet opening downwardly for discharge of the powdered fuel by gravity into the casing and means for controlling said discharge at a point adjacent the upwardly traveling side of the blast wheel 35 adjacent the periphery thereof.

3. In the combination defined in claim 2, 40 said means forming a closure for the outlet of the fuel hopper, and arranged to feed measured quantities of the powdered fuel to the outlet in fixed relation to the speed of the blast wheel.

OTTO A. KREUTZBERG.
